CLAIM

The ornamental design for a light, as shown (and described).

DESCRIPTION

FIG. 1 is a perspective view of a light showing my new design;
FIG. 2 is a front elevational view thereof;

FIG. 3 is a rear elevational view thereof, wherein the broken
lines illustrate environmental structure that forms no part of
the claimed design;

FIG. 4 is a left side view thereof;

FIG. 5 is a right side view thereof;

FIG. 6 is a top plan view thereof; and,

FIG. 7 is a bottom plan view thereof, wherein the broken lines
illustrate environmental structure that forms no part of the
claimed design.
